CLAIM

The ornamental design for a roller skate, as shown and described.

DESCRIPTION

FIG. 1 is a perspective view of a roller skate showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and

FIG. 9 is a partial enlarged view of portion 9 in FIG. 1; and, FIG. 10 is a partial enlarged view of portion 10 in FIG. 2. The evenly broken line in the drawings depicts unclaimed portions of the roller skate; the dash-dot broken line discloses unclaimed boundaries of the isolated and enlarged views; the broken lines form no part of the claimed design.

1 Claim, 10 Drawing Sheets
